UNITED STATES PATENT OFFICE.

AUSTIN R. ALLEN, OF BIGSPRING, NEBRASKA.

CRUTCH.

1,253,117.

Specification of Letters Patent. Patented Jan. 8, 1918.

Application filed March 23, 1917. Serial No. 156,922.

To all whom it may concern:

Be it known that I, AUSTIN R. ALLEN, a citizen of the United States, residing at Bigspring, in the county of Deuel and State of Nebraska, have invented certain new and useful Improvements in Crutches; and I do hereby declare the following to be a full, clear, and exact description of the invention, such as will enable others skilled in the art 10 to which it appertains to make and use the same.

This invention has for its object to provide an improved crutch embodying novel features of construction permitting the 15 crutch to be adjusted to adapt it for use by persons of various types and also of various arm lengths.

Another object is the provision of means for securely holding parts of the crutch in 20 adjusted position.

With these and other objects in view, the invention consists in the novel construction, combination and arrangement of parts as will be hereinafter specifically described, 25 claimed and illustrated in the accompanying drawing, in which:

Figure 1 represents a side elevation, partly in section, of the improved crutch.

Fig. 2 represents a perspective view of the 30 securing clip for the adjustable leg of the crutch,

Fig. 3 represents a perspective view of the 35 bolt for securing the hand grip in adjusted position between the arms or side members of the crutch,

Fig. 4 represents a fragmentary longitudinal sectional view on an enlarged scale of the perforated portion of one of the side members or arms of the crutch, and

Fig. 5 represents a fragmentary longitudinal section view on an enlarged scale of the lower terminal of one of the side members or arms of the crutch.

Referring to the drawing in detail, where- 45 in similar reference numerals indicate corresponding parts throughout the several views, the numeral 5 indicates an arm rest of an approved shape in which are secured the upper terminals of the side members or 50 arms 6, having converging lower terminals 7 provided with parallel lower terminals 8.

The medial portions of the side members 6 are formed with a series of spaced trans- 55 verse bolt-receiving openings 9, receiving a bolt 10 having a head 11 at one terminal and

screw threads at the opposite terminal receiving a nut 12. A hand grip 13 is ar- 60 ranged between the side members 6 and is formed with a longitudinal opening 14 ac- commodating the bolt 10.

The adjustable leg of the crutch, designated generally by the numeral 15, is formed with a plurality of uniformly spaced trans- 65 verse openings 16. The adjustable leg is slidably received between the parallel ter- minals 8 of the side members and the aper- 70 tures 16 are adapted to be moved into regis- tration with spaced apertures 17 formed in the parallel portions 8 of the side members. The apertures 17 in the side members are ar- 75 ranged a distance apart corresponding to the space between three of the openings 16 in the adjustable leg, so as to permit of a wider range of adjustment of the leg and consequently a more accurate adjustment of 80 the crutch to adapt it to the varying re- 75 quirements of the individuals by whom it is used.

A substantially U-shaped securing clip, in- 80 cluding parallel legs 18 and curved web por- 85 tion 19, is utilized to secure the leg 15 in ad- justed position between the side members of the crutch; the legs 18 of the clip, which are threaded, are inserted through the spaced apertures 17 in the side members and 90 through apertures 16 in the adjustable leg which are alined therewith. Nuts 20 are 95 threaded upon the terminals of the legs 18 and, when properly adjusted, draw the par- 100 allel ends 8 of the side members together, thereby firmly clamping the adjustable leg in adjusted position. Owing to the curva- 105 ture of the web portion 19, the medial por- tion thereof is permanently held in spaced relation to the adjacent portion of the side member 6, thereby providing a space 21 of adequate size to receive the tip of the finger or the point of a tool to facilitate re- 110 moval of the clip from the crutch in making the desired adjustment of the leg.

In use, it is evident that the hand grip 13 may be adjusted longitudinally of the crutch and may be secured in adjusted position at any point throughout the length of the se- 115 ries of apertures 9. It is also evident that an exceptionally accurate adjustment of the leg 15 with relation to the side members 6 of the crutch may be had by moving the rela- 120 tively closely arranged openings 16 in the adjustable leg into registration with the 110

openings 17 in the side members, and subsequently securing the leg in position by the securing clip.

What I claim is:

5. 1. An adjustable crutch including an arm rest, side members connected with the arm rest, the terminals of the side members opposite the arm rest having spaced apertures therein, an adjustable leg having apertures, 10 a substantially U-shaped clip extending through the aligned openings in the side members and adjustable leg for securing the latter in adjusted position, the web portion of the clip being curved to provide a handle 15 to facilitate removal of the clip from the crutch.
2. A crutch including an arm rest, side members connected with the arm rest having spaced openings in the terminals oppo-

site the arm rest, an adjustable leg having 26 openings therein arranged in closer relation than the spaced openings in the side members, a substantially U-shaped clip including a curved web portion and parallel legs extending through the aligned openings in 25 the side members and leg, the web portion of the clip being curved to provide a handle to facilitate removal of the clip from the crutch, and means associated with the clip 30 for drawing the terminals of the side members together, and securely clamping the bolt.

In testimony whereof I affix my signature in presence of two witnesses.

AUSTIN R. ALLEN.

Witnesses:
